ILLUMINATED SIGN

Theodore F. McFall, El Cerrito, Calif.

Application February 15, 1944, Serial No. 522,494

4 Claims. (Cl. 40—130)

1

An object of my invention is to provide a new type of luminous sign which provides a luminous background for the characters supported on the sign. The device is simple in construction and attractive.

Other objects and advantages will appear in the following specification and the novel features of the device will be particularly pointed out in the appended claims.

Figure 1 is a perspective view of a sign with characters secured thereto;

Figure 2 is a vertical section taken substantially along the line 2—2 of Figure 3, and

Figure 3 is a transverse section taken substantially along the line 3—3 of Figure 2.

While I have shown only the preferred form of my invention, it should be understood that various changes or modifications may be made within the scope of the appended claims without departing from the spirit and scope of the invention.

A sign supporting characters is disclosed in Figures 1, 2 and 3. The sign, indicated generally at E has an opaque semi-cylindrical base 21 that is secured to lugs 22 by screws 23. The lugs 22 are integral with end plates 24 which in addition have side lugs 25, against which the sides of the base bear, and top center lugs 26. Angle members 27 extend the length of the base and have their ends secured to the side lugs 25 by screws 28. The downwardly extending sides of the angles 27 carry tabs 13 spaced the desired distances apart for supporting the letters D spelling the word "Gifts." The character D may be hollow and may be made out of any material desired. The characters may also be opaque, translucent or transparent.

Bolts 29 secure the tabs 13 to the angles 27 and the bolts also secure a translucent U-shaped shield 30 in place. The shield 30 encloses illuminating means such as a globe or a luminaline tube 32. The shield also acts as an illuminated background for the characters of the sign. Screws 33 secure the shield to the top lugs 26. U-shaped guides 34 integral with the top lugs 26 and with the end plates 24 support and hold the shield in proper shape.

The globes 32 are received in sockets 35 that extend through openings 36 provided in the end plates 24. The socket is secured to a support 37 by a standard screw 38. The support in turn is attached to an annular shoulder 39 formed in a hollow opaque end piece 40 by screws 37a. Screws 41 secure the end plates 24 to the end pieces 40.

From the foregoing description of the various parts of the device, the operation thereof may be readily understood.

The character D may take any shape desired. The tabs secure the characters to the supporting surface.

2

In making the sign, the base 21, angle members 27 and shield 30 may be cut to form pieces of any desired length. The sign is then assembled in the manner already described. When the sign is lighted, the opaque letters will stand out against an illuminated background. The tabs will be hidden from view. The message of the sign may be changed if desired by merely changing the characters. The sign is designed to be constructed by the purchaser who buys the necessary parts and then assembles the parts.

The angle members 27 are spaced from the sides of the shield 30 by the thickness of the tabs 13 and this provides ventilating slots 42 for the passage of heated air therethrough. The sign is kept ventilated in this manner, the heated air generated by the tubes 32 passing through the slots 42.

I claim:

1. In a sign, a pair of supporting members spaced from and paralleling each other, said supporting members having horizontal portions, characters mounted on the horizontal portions, a translucent U-shaped shield carried by the supporting members and bridging the space therebetween, and lighting means for illuminating the shield.

2. In a sign, a pair of angle members spaced from and paralleling each other, a translucent U-shaped shield carried by the members and bridging the space therebetween, lighting means housed within the shield, characters placed on both sides of the shield and resting on the members, and tabs for securing the characters to the members.

3. In a sign, a pair of angle members spaced from and paralleling each other, said angle members having horizontal and vertical portions, characters mounted on the horizontal portions, tabs secured to the vertical portions and to the characters for holding them in place, a translucent U-shaped shield carried by the angle members and bridging the space therebetween with the exception of the thickness of the tabs, the space between the shield and the angle members providing ventilation slots, and lighting means housed within the shield.

4. In a sign, a frame having parallel horizontal portions for supporting letters, an inverted U-shaped member disposed between the horizontal portions and permitting light rays to pass therethrough, end pieces for the frame and U-shaped member, and lighting means carried by at least one of the end pieces and having its illuminating portion coinciding with the end of the U-shaped member abutting the end piece.
